METHOD OF FORMING VEILS

Chester Blumberg, Chicago, Ill.

Application January 23, 1933. Serial No. 652,977

5 Claims. (Cl. 2—207)

The invention relates to veils and has more particular reference to forming a rectangular piece of mesh material into a veil having inner and outer edges of arcuate shape and which will lie flat with all the material in the same plane.

An object of the invention is to utilize a substantially rectangular piece of veiling material for making an arcuate shaped veil and wherein the free edge of the material will be gathered in a manner preventing the formation of wrinkles or pleats, and which can be set before the draw cord is removed.

Another object of the invention resides in the provision of a method for making veils of the shape described having the desired result of producing two veils of substantially identical shape for each forming operation.

A further object resides in the method of making veils in which suitable mesh material is given its initial shape by application to a form which will permit steaming and ironing of the material to set the shape while remaining on the form.

With these and various other objects in view the invention may consist of certain novel features of construction and operation as will be more fully described and particularly pointed out in the specification, drawing and claims appended hereto.

In the drawing which illustrates an embodiment of the device and wherein like reference characters are used to designate like parts—

Figures 1 and 2 are elevational end views, respectively, showing the application of the veiling material to the form;

Figure 3 is an elevational view illustrating the manner of gathering the free edges of the material to hold the same tightly on the form;

Figure 4 is a plan view of a completed veil formed by the present invention; and Figure 5 is a plan view similar to Figure 4 showing the veil in a horseshoe shape.

The veiling material 10 as shown in Figure 1 may comprise any suitable mesh material such as hair braid or fine net, the former, however, being preferable as it is easier to work, takes a more permanent set, and can be separated so that the resulting pieces have a clean edge which will not ravel. The veiling material is cut into a rectangular or square form, depending on the size of the completed veil, and is folded to provide two thicknesses of material. The circular form 12 is then located between the folded material, as shown in Figure 2. It will be more clearly understood as the description proceeds that the length of the material determines the size of the com-

pleted veil and that the width of the piece 10 must be twice that of the width of the completed veil, as the material is folded through its center and then applied to the form 12 as described.

The next step in the present method is to gather the free ends of the material to cause the same to assume the shape of the form 12. This is accomplished by threading a draw cord 14 through the loops 16 of the free edge, drawing the cord taut and tying the same, as shown in Figure 3, to hold the material tightly on the form. With silk net and similar materials it is often possible to select a thread running lengthwise of the material which will serve as a draw cord to gather the free edge of the material in the same manner as described. With the veiling material thus held on the form 12 the same is then steamed in any suitable manner and subsequently ironed in order to set the material.

After the material has remained on the form for a length of time to insure thorough drying the draw cord 14 is removed and the material taken from the form. By the initial fold given the material two veils are produced with each forming operation, it being only necessary that the material be separated along the folded edge 18 and in this respect hair braid has been found very desirable, as the separation can be more readily accomplished with both veils having a clean unsevered outer edge. Separating the veils along the folded edge in the manner described is not to be considered as limiting the present invention as other material may be cut in the usual manner. Each veil is now ironed separately in any suitable manner to completely remove all wrinkles and additionally increase the stiffness of the veil. Two completed veils such as 20, Figure 4, result from the above method. The outer edge is provided with a number of scallops, which result from the separation of the material along the fold 18, giving a desirable effect and adding to the appearance of the veil, as is also the slightly rounded points 22 on the inner edge.

Another feature of the invention resides in the use of a wire form which can be distorted from its circular shape by flattening the sides, making the form oblong, with the result that the veiling material held on the form can be given a horseshoe shape as shown in Figure 5. Shaping the veil by distorting the form takes place only while the same is being steamed and ironed, whereupon the material is removed and given its final set. The method in other respects is similar to that previously described.

By the present method four veils can be formed.

by one operation, as it is possible to apply to the 5 form material of a length to completely encircle the form which can be subsequently cut along the fold 18 and then transversely into veils of the correct size. Cutting the material along the fold is required if the completed veil is to be of a single thickness, although for veils of silk net and similar material a double thickness is often desired and therefore this step in the method is 10 sometimes omitted.

It is to be understood that I do not wish to be limited by the exact embodiment of the device shown, which is merely by way of illustration and not limitation, as various and other forms of 15 the device will of course be apparent to those skilled in the art without departing from the spirit of the invention or the scope of the claims.

I claim:

1. The method of forming veils which 20 comprises applying a folded piece of veiling material to a substantially circular form, drawing the free edges of the material together by a draw cord to hold the material tightly on the form, steaming and ironing the material while held on the form, and finally separating the material along its 25 folded edge.

2. The method of forming veils which 30 comprises folding a piece of veiling material along its center, applying the same to a form so that one thickness is located to each side thereof, drawing the free edges of the material to hold the same tightly on the form, and finally severing the material along the folded edge.

3. The method of forming veils which comprises folding a piece of veiling material along its center, applying the same to a form so that one thickness is located to each side thereof, drawing the free edges of the material to hold the same tightly on the form, steaming and ironing the material while on the form to set the same, removing the material from the form and finally ironing to remove all wrinkles and to give the veil increased stiffness.

4. The method of forming veils which comprises folding a piece of veiling material along its center, applying the same to a form so that one thickness is located to each side thereof, drawing the free edges of the material to hold the same tightly on the form, steaming and ironing the material while on the form to initially set the same, removing the material from the form and severing the same along the folded edge into two veils, and finally ironing to remove all wrinkles.

5. The method of forming a plurality of veils from one forming operation which comprises folding a piece of veiling material to provide a double thickness of material, applying the folded 100 strip to a form to give each thickness the shape of the form, and finally severing the material along the folded edge and cutting each veil transversely to secure veils of the size desired.
